**ADJUSTABLE BLANK FIRING ATTACHMENT
FOR AUTOMATIC FIREARMS**

Earle M. Harvey, Agawam, Mass., assignor to the United States of America as represented by the Secretary of the Army

Filed May 14, 1963, Ser. No. 280,473

4 Claims. (Cl. 89—14)

(Granted under Title 35, U.S. Code (1952), sec. 266)

The invention described herein may be manufactured and used by or for the Government for governmental purposes without the payment to me of any royalty thereon.

This invention relates to blank firing attachments for automatic firearms and is more particularly directed to an attachment which can be readily adjusted to vary the gas pressure imparted to the recoiling parts of the firearm.

In order to permit the utilization of blank ammunition for the training of military personnel in the handling and operation of automatic firearms, the muzzle end of the barrel is generally fitted with an attachment having a fixed orifice for restricting the forward flow of the propellant gases to provide sufficient pressure to function the recoiling parts of the firearm. While these blank firing attachments produce the required automatic operation of the firearm, the orifice must be designed so that the pressure of the propellant gases will be considerably greater than the energy required to function the recoiling parts.

In many firearms the excessive recoil forces produced by conventional blank firing attachments are readily absorbed by the recoiling parts of the firearm. However, in some firearms, the energy imparted to the recoiling parts must be maintained within a relatively narrow range. For example, in the Cal. 7.62 mm. M73 Machine Gun, insufficient recoil movement of the bolt will result in a failure to eject the fired cartridge case while excessive recoil velocity of the bolt will prevent the critical transfer of the fired case to a pivotal gripper member for subsequent ejection through the bottom of the firearm receiver. Consequently, considerable difficulty has been experienced in selecting the proper orifice size to be employed in the blank firing attachment.

This problem is even further complicated by the fact that the peak pressure produced by blank ammunition normally varies from one production lot to another. In addition, any prolonged or unusually severe operation of the firearm serves to vary the energy requirements of the recoiling parts. Another factor responsible for variations in the gas pressures provided by blank firing attachments is the tolerances permitted in the dimensions of the attachment itself. Also, the manner in which the firearm is mounted plays an important role in determining the power requirements of the recoiling parts. As a result, previous attempts to selectively fit a blank firing attachment of the particular power requirements of the M73 firearm have required considerable testing with a plurality of attachments.

Accordingly, it is a basic object of this invention to provide a simple, rugged, and compact blank firing attachment which can be readily adjusted to yield the optimum recoil energy required by the particular firearm on which the attachment is mounted.

A more specific object of the present invention is to provide an adjustable blank firing attachment in which the orifice for the passage of the propellant gases may be readily increased or decreased in size without the necessity for any replacement of parts or removal of the attachment from the firearm.

It has been found that these objects may be advantageously accomplished by providing a blank firing attachment with a rotatable transverse pin having an eccentrically formed groove of predetermined contour dis-

2

posed in the path of the propellant gases issuing from the muzzle end of the firearm barrel. One end of the pin is suitably slotted to permit an index mark thereon to be rotated and locked into alignment with a plurality of 5 graduations which are consecutively numbered to correspond with the size of the cross-sectional area disposed in the path of the escaping gases at any angular position of the eccentric groove.

The specific nature of the invention as well as other 10 objects and advantages thereof will clearly appear from a description of a preferred embodiment as shown in the accompanying drawings in which:

FIG. 1 is a longitudinal section through the muzzle 15 end of an automatic firearm provided with the blank firing attachment of the present invention adjusted for maximum passage of the recoil gases;

FIG. 2 is a right side view of the attachment showing the adjusting screw rotated to the upper limit of the calibrated scale;

FIG. 3 is a cross-sectional view taken along line 3—3 20 of FIG. 1 to show the transverse configuration of the adjusting screw;

FIG. 4 is a fragmentary view similar to FIG. 1 but 25 showing the adjusting screw positioned for minimum gas passage;

FIG. 5 is a side view similar to FIG. 2 but showing the adjusting screw in the minimum position to FIG. 4; and

FIG. 6 is a sectional view taken along line 6—6 in 30 FIG. 5 to show the transverse configuration of the locking means for the adjusting screw.

As shown in the figures, the blank firing attachment of this invention comprises a generally rectangular block 12 adapted to be threaded as shown at 14 to the front 35 end of a bearing 15 surrounding the muzzle end of a longitudinally slid able barrel 16. Immediately forwardly of threads 14, the interior of block 12 is formed with an annular stop shoulder 18 designed to contact the front end of bearing 15 which is in turn secured to a sleeve 17 suitably fixed in the front end of a barrel jacket 19.

Extending forwardly of stop shoulder 18 is a conical 40 well 20 terminating in a forwardly opening orifice 22 in longitudinal alignment with the bore axis of barrel 14. Orifice 22 is partially intersected by a hole 24 which extends transversely through block 12 to terminate in an enlarged recess 26 formed in one side of block 12 by the intersection of a circular portion 28 and the open end of a U-shaped section 30.

Transverse hole 24 serves to rotatably seat a pin 32 45 having an enlarged cylindrical head 34 engageable in circular portion 28. The underside of head 34 is annularly beveled, as indicated at 36, to mate with a correspondingly shaped seat 38 provided in the floor of circular portion 28 and of sufficient depth to position the top of head 34 50 into flush alignment with the outer wall surface of block 12. Thus, a radially extending index arrow 40 inscribed on the top of head 34 can be accurately aligned with each 55 of a series of graduation marks 42 radially disposed about substantially half of the circumference of circular portion 28. The desired alignment is achieved by rotating pin 32 in the proper direction and head 34 is, therefore, 60 suitably slotted, as indicated at 44, in FIG. 2 to receive the blade end of a screwdriver or other similar tool.

The body of pin 32 is formed with a substantially 65 central bearing surface 45 which is grooved, as shown at 46, to provide an eccentric surface 48 of progressively increasing depth. The required eccentric contour may be effectively obtained by a series of adjacent angular cuts which will provide a plurality of flat surfaces disposed at 70 progressively increasing depths relative to the exterior periphery of pin 32. Or, if preferred, surface 48 may be helically formed to provide a contour which will not be

interrupted by the ridges formed at the intersection of surfaces of different angularity. Groove 46 is so located along the axis of pin 32 and is of such width that, when the latter is properly seated in block 12, the opposite walls of groove 46 are positioned in tangential alignment with the corresponding walls of orifice 22.

A bolt 52 is threadably mounted in block 12 through the center of U-shaped section 30 along an axis substantially parallel to that of pin 32 and is provided with an enlarged head 54 adapted to overlie a stepped surface 50 extending circumferentially along slightly more than half of the peripheral edge of head 34 on pin 32. A pair of crossed slots 56 on bolt head 54 provide access for a suitable tool by means of which bolt 52 may be rotated into and out of locking engagement with surface 50 on adjusting pin 32. The terminal ends of stepped surface 50 are arcuately formed, as shown at 58, to cooperate with the circular periphery of locking bolt 52 for limiting the rotation of adjusting pin head 34 between minimum and maximum gas passage positions of eccentric groove 46. In addition, index arrow 49 is located on head 34 to align with the corresponding graduation mark 42 at the beginning or end of the calibrated scale whenever adjusting pin 32 is in one of these limiting positions.

Thus, when it is desired to utilize an automatic firearm for training purposes, the blank firing attachment is simply threaded onto the muzzle end of the barrel, or the bearing 15 in the particular firearm depicted in the drawings, and adjusting pin 32 rotated until index arrow 49 thereon is aligned substantially midway of graduation marks 42 and locked in such position by tightening bolt 52. When a blank cartridge is subsequently fired, the forward flow of the propellant gases will be partially blocked by the walls of conical well 20 as well as by eccentric groove 46 in adjusting pin 32. This restricted gas flow will, of course, increase the gas pressure in the firearm and provide the necessary recoil of the moving parts.

However, if such pressure is too low or too high, as evidenced by the particular action of the recoiling parts, bolt 52 is loosened and adjusting pin 32 rotated in the direction and to the extent estimated to yield the proper firearm operation and locked in such position. Another blank cartridge is fired and the foregoing adjustment repeated until the moving parts are deemed to recoil in the same manner and at the same velocity as would be the case if live ammunition were used.

Thus, there is here provided a blank firing attachment which can be quickly and easily adjusted to provide optimum firearm operation without the necessity for removing the attachment or any of the parts thereof from the firearm. Consequently, the firearm may continue to be utilized for training purposes regardless of any undue variation in the power characteristics of the ammunition or any change in the energy required to recoil the moving parts. Furthermore, the use of an eccentric surface for blocking the forward flow of the propellant gases permits the blank firing attachment to be adjusted in extremely small increments and over a relatively wide range.

Although a particular embodiment of the invention has been described in detail herein, it is evident that many variations may be devised within the spirit and scope thereof and the following claims are intended to include such variations.

1 claim:

1. A blank firing attachment for a recoil operated firearm having a reciprocating barrel, said attachment comprising a block having an axial orifice therethrough for the passage of the discharge gases produced by the firing of a blank cartridge, means for securing said attachment to the firearm in axial alignment with the muzzle end of the barrel, means for adjusting the size of said orifice to control the flow of gases therethrough and thereby provide sufficient pressure against the muzzle end of the barrel to simulate the action normally impacted to the recoiling parts by live ammunition, and means for locking said gas control means in any of a plurality of adjusted positions.

2. The combination defined in claim 1 wherein said means for adjustably controlling the flow of gases through said orifice in said blank firing attachment comprises a rotatable pin transversely mounted in said block to partially intersect said orifice at substantially right angles thereto, said pin having a groove of progressively increasing depth and disposed in intersecting alignment with said orifice.

3. A blank firing attachment for a recoil operated firearm having a reciprocating barrel, said attachment comprising a block having a conical well communicating with a forwardly disposed axial orifice for the passage of the discharge gases produced by the firing of a blank cartridge, means for securing said attachment in axial alignment with the muzzle end of the barrel, a rotatable pin transversely mounted in said block to partially intersect said orifice at substantially right angles thereto, said pin having an enlarged head with an index arrow inscribed thereon, a plurality of graduations inscribed on the side of said block and radially disposed about said enlarged head for selective alignment with said index arrow, said transverse pin having an eccentric groove therein of progressively increasing depth disposed in intersecting alignment with said axial orifice, a step surface peripherally formed in said enlarged head and radially oriented relative to said eccentric groove to align said index arrow with said graduations in direct accordance with the extent of restriction of said axial orifice, and means for locking said adjusting pin in any of a plurality of rotated positions.

4. The combination defined in claim 3 wherein said means for locking said adjusting pin comprises a bolt threadably secured in said block with a head disposed to engage said step surface on said enlarged head of said adjusting pin and prevent rotation thereof.
